NEEDLE STRAIGHTENING CLAMP

Filed Feb. 3, 1930

Inventor:
Albert E. Parker
By Leonard L. Kalish
Attorney.

UNITED STATES PATENT OFFICE

ALBERT E. PARKER, OF PHILADELPHIA, PENNSYLVANIA

NEEDLE STRAIGHTENING CLAMP

Application filed February 3, 1930. Serial No. 425,646.

My invention relates to needle straightening clamps for spring beard needles of the type used in full fashioned flat knitting machines. In full fashioned machines individual needles are used and a sufficient number of them are held parallel to each other in fixed position in the needle bed. It is necessary at times during the operation of the machine to replace one or more of these needles in the needle bed, as they become damaged and unfit for further use, or to straighten them in case they become bent. When new needles are placed in the needle bed, it is necessary to see that they are perfectly straight and that the beards are properly aligned with the shanks, for it frequently happens that even new needles are not free from these defects. This operation must be carried out on all needles before placing them in the needle bed in order to insure proper alignment thereof, so that a perfect fabric will result from the knitting operation.

It has been customary to inspect these needles one by one by the knitter and to straighten the shanks and align the beards by means of any suitable tool, such as pliers. Naturally considerable experience and skill is required to do this perfectly by hand, and in addition a considerable amount of time is required. It is therefore an object of this invention to provide means whereby a plurality of needles may be inspected and straightened at one time; by means of which much less time is required; and by means of which a knitter having relatively less experience and skill will be enabled to secure perfect results.

Additional objects and advantages will be apparent from the following description and the accompanying drawing, which form part of this specification and in which

Figure 1 is a view of one face of the needle straightening clamp in upright position, embodying my invention.

Figure 2 is a view of the other face, the clamp being in horizontal position.

Figure 3 is a section on line 3—3 of Figure 1.

Figure 4 is a section on line 4—4 of Figure 2.

Figure 5 is a view of the base member and bed member with the curved plate removed, and

Figure 6 is a section on line 6—6 of Figure 1.

In the drawing the clamp is provided with the base member 7, having the hollow tubular collar 8 by means of which the clamp is suitably supported. A spindle 9 is provided, projecting from the machine bed or from any suitable support, having the flat portions 10 and 11 as shown in Figures 3 and 4. These flat portions are disposed vertically and horizontally for a reason to be explained. The collar 8 slides over the end of spindle 9, and is fixed on said spindle by tightening the wing head bolt 12, threaded into the collar 8, against said spindle 9, preferably at one or the other of said flat portions.

As shown in Figures 3 and 4, a bed 13, preferably of brass, is provided on one side of the base 7. This bed 13 has parallel grooves 14 into which the lower ends of the shanks of the spring beard needles may be placed, as shown. The bed is also provided with a horizontal series of holes 15, in line with the grooves 14, into which the turned over butt ends of the needle shanks may be placed, as clearly shown. The size of the grooves 14 and the holes 15, depend upon the gauge of the needles used, and may be made to take care of any given gauge, or may be made of such size as to take care of a certain range of gauges which differ but slightly from each other.

A curved plate 16 is provided to hold the needles in position in said bed 13 while they are being inspected. The lower end 17 of

the plate 16 is curved so as to space the upper end 19 properly in relation to the needles. The said lower end 17 takes into horizontal groove 18, formed in base 7, and the plate 16 is held fast against said base and said needles by tightening a wing head bolt 20, which has a collar taking against said plate. This bolt 20 passes through a hole 21 in base 7, and is threaded into a hole in said plate 16.

10

Operation

A group of needles are placed with their butts in adjacent holes 15, and their shanks in adjacent grooves 14, the plate 16 then 15 being fixed in position as explained. The clamp is then placed on spindle 9 in the position of Figure 3, with the bolt 12 taking against flat 10, which aids in ascertaining the upright position. Then by looking at 20 said needles from the side opposite the beards, i. e., from the right in Figure 3, the needles may be quickly inspected, straightened and lined up by means of pliers. The location of a group of needles alongside of 25 each other makes the straightening process much easier and quicker than when a single needle is inspected by the hand method. When this is done, the bolt 12 is loosened and turned to the position of Figure 4, the bolt 30 then being tightened against flat 11. In this position the beards may be quickly and easily inspected and lined up by means of any suitable tool. At this time the beards are in position to be openly viewed from above. 35 When the straightening or lining up is completed, the needles are removed from the clamp, and are ready for insertion into the machine bed.

I am aware that the invention may be embodied in other specific forms without departing from the spirit of essential attributes thereof, and I therefore desire the present embodiments to be considered in all respects as illustrative and not restrictive, 40 reference being had to the appended claims rather than to the foregoing description to indicate the scope of the invention.

I claim—

1. The method of straightening needles, 45 which consists in providing a clamp adapted to grip and to hold a plurality of needles in a coplanar position, said clamp being adapted alternately to be held in a fixed position and to be rotated about an axis, at the will of the operator; and gripping a plurality of needles in a coplanar position in said clamp, fixating said clamp, inspecting and adjusting said needles while in said plane; rotating the clamp so as to change the plane of said needles, and inspecting and adjusting said needles while in the new plane.

2. The method of straightening needles, 50 which consists in providing a clamp adapted to grip and to hold a plurality of needles in a coplanar position, said clamp being adapted

alternately to be held in a fixed position and to be rotated about an axis, at the will of the operator; and gripping a plurality of needles in a coplanar position in said clamp, fixating said clamp, inspecting and adjusting said needles while in said plane; rotating the clamp so as to change the plane of said needles, and inspecting and adjusting said needles while in the second planar position thereof, one of said planar positions being generally vertical, and the other being generally horizontal.

In testimony whereof, I have hereunto set my hand this 31st day of January, 1930.

ALBERT E. PARKER.
